CLAIM

The ornamental design for a therapy shoe, as shown and described.

DESCRIPTION

FIG. 1 is a perspective view of a therapy shoe showing our new design;

FIG. 2 is another perspective view thereof;

FIG. 3 is a right side elevational view thereof;

FIG. 4 is a left side elevational view thereof;

FIG. 5 is a front elevational view thereof;

FIG. 6 is a rear elevational view thereof;

FIG. 7 is a top plan view thereof;

FIG. 8 is a bottom plan view thereof; and,

FIG. 9 is an enlarged view of the therapy shoe shown within the area designated as 9 in FIG. 1.

The dashed broken lines in the drawings are for the purpose of illustrating portions of the therapy shoe that form no part of the claimed design. The dot-dashed broken lines in FIGS. 1 and 9 show the boundary of the enlarged view and form no part of the claimed design.
